UNITED STATES PATENT OFFICE

2,604,184

ELECTROSTATIC PRECIPITATOR

Ray W. Warburton, Medfield, and Frank W. Morley, Westwood, Mass., assignors to Westinghouse Electric Corporation, East Pittsburgh, Pa., a corporation of Pennsylvania

Application December 1, 1948, Serial No. 62,932

12 Claims. (Cl. 183—7)

1

This invention relates to electrostatic precipitators for the removal of small foreign particles, such as dust, from gases, such as air, and relates more particularly to systems for the washing of the electrodes of such precipitators.

The electrodes of electrostatic precipitators, after periods of use, become so coated with collected matter that for efficient operation it is necessary to clean them. A satisfactory method of cleaning the electrodes is to wash them down with a flushing liquid, such as a light oil. In some installations, where large volumes of gas are treated, a large precipitator is used and one section of it is rendered inactive and its electrodes washed while the other sections remain active. Then the one section is put back into service while another section is rendered inactive for the washing of its electrodes. There are many operations involved in the removal of a portion of a precipitator from service for the washing of its electrodes and in placing it back in service. Its gas inlet and outlet must be closed before the washing operation, and afterwards opened; its electrodes must be disconnected from their power supply source before the washing operation, and afterwards reconnected. Its electrodes must be washed the proper amount, and then, after washing, must be properly drained before being placed back into service. The various controls must be operated in the proper sequence and must be accurately timed. In a multi-section precipitator, much of the washing and other equipment is common to all of the sections, and it has been found difficult to isolate one section for the washing of its electrodes without interfering with the operation of the other sections. Another disadvantage of a multi-section precipitator is the difficulty of adapting it to handle different volumes of gas.

This invention provides a relatively small, electrostatic precipitator which can be used alone for cleaning a relatively small volume of gas, or in multiple for cleaning any desired volume of gas. Each precipitator contains its own equipment for automatically removing it from service, for washing its electrodes, and for returning it to service. All an attendant has to do is to actuate one control when a precipitator is ready for its electrodes to be cleaned, following which, its gas inlet and outlet are closed, its electrodes are disconnected

5 from their power supply source, the pump for supplying the washing liquid to the spray headers is started, the headers containing the electrode washing nozzles are moved from a parking position spaced from one end of the electrodes where they are normally out of the gas stream, to the other end thereof where the movement of the headers is reversed and they are returned to the parking position. When the headers reach the 10 end of the electrodes adjacent the parking position on their outward movement, the spray of the flushing liquid upon the electrodes is started, provided the temperature of the liquid is above a predetermined minimum. If not, the liquid is 15 not sprayed, and the movement of the headers is stopped until the liquid reaches the proper temperature. When the headers are returned to the parking position, they are stopped there, and a timer is started which provides a delay period 20 suitable for the draining of the flushing liquid from the electrodes, following which, all controls are returned to normal, the pump is stopped, the gas inlet and outlet are opened, the electrodes are reconnected to their power supply source, and the 25 precipitator is returned to service. The operations described in the foregoing are automatic, are in proper sequence, and are properly timed.

Another feature of the invention is that when an attendant initiates the described operation in 30 a particular precipitator, a light on the control panel is lighted, indicating that that precipitator is out of service, and a timer is started which, if the operations described in the foregoing have not been completed in the proper time, will actuate an alarm signal.

An object of the invention is to provide an improved, automatically operated, control system for removing an electrostatic precipitator from service, for washing its electrodes, and for then 40 restoring it to service.

The invention will now be described with reference to the drawing, of which:

Fig. 1 is a diagrammatic view illustrating the connection of several electrostatic precipitators 45 embodying this invention, in multiple in common gas inlet and outlet ducts;

Fig. 2 is a diagrammatic view illustrating the connection of the precipitators of Fig. 1 to a common, flushing liquid supply source;

Fig. 3 is a diagrammatic view, in side elevation,

of a portion of an electrostatic precipitator with electrode washing equipment and controls therefor, embodying this invention;

Fig. 4 is a diagrammatic view showing a partial front elevation of the precipitator of Fig. 3, and

Fig. 5 is a simplified circuit schematic illustrating the connections of the switching mechanisms on control panel to the components operated thereby.

Referring now to Fig. 1, the casings of the four similar electrostatic precipitators A, B, C, and D are shown connected in multiple in a common gas inlet duct 10 and a common gas outlet duct 11. More or fewer precipitators could be used, depending upon the volume of dirty gas to be cleaned.

Fig. 2 illustrates the four precipitators with their control panel, and with a common flushing liquid sump 12. A common, liquid supply pump 13 driven by an electric motor 14, supplies flushing liquid from the sump 12 to each of the precipitators when it is its turn to be washed. The pump 15, driven by the electric motor 16, recirculates the liquid in the sump 12 through the cleaner 17 in which the foreign matter therein is removed, and through the heater 18 which maintains the liquid at the proper temperature, which may be 180° F. for handling. The liquid used may be a light, petroleum base oil.

Referring now to Figs. 3 and 4, the casing of each of the precipitators contains the superimposed collector cells 20 with the wire ionizer electrodes 21 and the tubular ionizer electrodes 22 arranged upstream with respect to gas flow, thereof. The vertical spray header 24 is movable by the screws 25 threaded into its end fitting 26, horizontally between the ionizer electrodes and the collector cells, and has the upstream spray nozzles 27 for spraying liquid upon the ionizer electrodes, and has the downstream spray nozzles 28 for spraying liquid upon the plates of the collector cells. The vertical spray header 30 is movable by the screws 29 threaded into its end fitting 31, and has the upstream nozzles 37 for spraying liquid upon the collector cells from their rear.

The screws 25 and 29 are rotated by the electric motor 32 through the belt 33, the pulley 34, the sprockets 35, and the chain 36.

The inlet louvres 38 are in the upstream side of the precipitator casing, and the outlet louvres 45 are in the downstream side of the casing. The components described in the foregoing are disclosed in detail in the R. L. Lincoln application, Serial No. 52,329, filed October 1, 1948.

Normally during the gas cleaning operation, the headers 24 and 30 are located in the parking space 43 which is an open space to one side of the inlet, the outlet, and the electrodes of the precipitator, so as to be completely outside the gas stream being cleaned.

When one of the precipitators is ready for its electrodes to be washed, an attendant inserts a key in its lock 49, and rotates the key. This actuates controls in the panel 50 which set up electric circuits causing the following sequence of operations: the relay 71 is energized by the movement of the switch 72 by the key in the lock 49, against the contact 96, and pulls up its armature 73 against the contact 74 closing the energizing circuit of the wash signal 43. At the same time the relay 75 is energized and pulls up its armature 76 against the contact 77 closing the energizing circuit of the timer 51 for the alarm 52. At the same time the relay 78 is energized

and pulls up its armature 79 against the contact 80 which is in a circuit including the drain timer 53 and normally open contacts of the switch 68, placing the timer 53 in condition for operation when the contacts of the switch 68 close. At the same time the relay 97 is energized and pulls up its armature 98 against the contact 99 and closes the energizing circuit including normally closed contacts in the drain timer 53 and the thermostat 54, of the pump motor 14, starting the pump if the temperature of the liquid in the sump where the thermostat is located, is above say 180° F. At the same time the relay 81 is energized and pulls up its armature 82 against the contact 83 which is in a circuit including the solenoid 55 which actuates the valve 56 in the liquid supply piping to the headers, the thermostat 65 and contacts in the switch 44. At the same time the relay 85 is energized and pulls up its armature 86 away from the contact 87 opening the normally closed, energizing circuit of the solenoid 57 which actuates the valve 58 in the liquid supply line to the cylinders 60 and 61.

The energizing circuit of the power pack 41 includes normally closed contacts of the single-pole, double throw switch 62.

The input connections to the reversing circuit 67 of the motor 32 includes normally open contacts of the switch 62, normally closed contacts of the switch 68, and the armature 92 and the contact 93 of the relay 91.

When the solenoid 57 is deenergized by the relay 85, it opens the valve 58, causing liquid to be supplied to the hydraulic cylinders 60 and 61 which then act to close the inlet louvres 38 and the outlet louvres 45. The closing of the inlet louvres actuates the switch 62 which opens the energizing circuit of the power pack 41, and closes the energizing circuit to the motor reversing circuit 67, causing the motor 32 to be energized, following which, it starts to move the headers 24 and 30 from the parking space towards the collector cells.

When the header 24 reaches the left hand end (facing Fig. 4 of the drawing) of the collector cells, it trips the switch 44 and completes through the thermostat 65 in the liquid supply piping to the headers, the energizing circuit of the solenoid 55 of the valve 56, if the temperature of the liquid is above 70° F., so that liquid is supplied to the spray nozzles in the headers. If the temperature is below 70° F., the thermostat 65 opens the supply circuit to the motor 32 by energizing the relay 81 which pulls up its armature 92 away from the contact 93, and opens the energizing circuit of the solenoid 55. This results in the closing of the valve 56 and the prevention of the supply of liquid to the spray nozzles in the headers, and in the stopping of the header motor 32. The liquid is then recirculated until it reaches 70° F., at which time liquid is supplied to the headers and the header motor is started.

When the header 24 reaches the right hand end (facing Fig. 4 of the drawing) of the collector cell, it trips the switch 66 in the motor reversing circuit, causing it to close the energizing circuit of the solenoid 94 which then retracts its plunger to which the reversing switch of the motor reversing circuit is attached, causing the field and armature of the motor to be so connected as to cause the motor to reverse. The motor then moves the headers back towards the parking space 43. When the header 24 reaches the switch 44, it again trips the

switch, causing it to open the circuit of the solenoid 55 and to thereby cut off the supply of liquid to the spray nozzles. The headers continue to move until they reach the parking space 43 where the header 24 trips the switch 68 which then opens the motor reversing circuit 67 and stops the header motor 32.

At this time the switch 68 closes contacts completing the circuit to the drain timer 53, causing it to start timing. After a period of 10 time sufficient for the sprayed electrodes to have drained properly, the timer 53 first stops the pump motor 14 for discontinuing the building up of oil pressure, and then closes the energizing circuit of the solenoid 95 which moves the switch 72 from the contact 96, and opens the energizing circuit of the relays 71, 75, 78, 81 and 85 and thus resets the controls in the control panel to normal, following which the valve 56 is closed, the hydraulic cylinders 60 and 61 open the inlet and outlet louvres, the pressure in the cylinders being released through the drain pipe 70, the power pack 41 is again energized, the wash signal 50 is turned off, and the alarm timer 51 is deenergized.

If for any reason the sequence of operations described in the foregoing is not completed in the proper time, the alarm 48 is actuated by the timer 51.

The timers 51 and 53 are conventional reset timers such as are manufactured by the Eagle Signal Company, and which reset their contacts to normal when deenergized.

Fig. 3 illustrates the switches 44, 66 and 68 schematically without showing their physical locations which are shown by Fig. 4.

The precipitator is now back in service, and the attendant can remove the key from the lock 49, and place it in the lock of the next precipitator to be washed, following which the sequence of operations described in the foregoing is followed in that precipitator.

While one embodiment of the invention has been described for the purpose of illustration, it should be understood that the invention is not limited to the exact apparatus and arrangement of apparatus illustrated, as modifications thereof may be suggested by those skilled in the art, without departure from the essence of the invention.

What is claimed is:

1. An electrostatic precipitator comprising a casing having a gas inlet and a gas outlet, electrodes in said casing between said inlet and outlet, header means movable alongside said electrodes for washing same, means for supplying liquid to said header means, damper means for preventing the flow of gas through said inlet and outlet, means for closing said damper means, and means including means actuated when said damper means is closed, and including means responsive to the temperature of the liquid supplied by said liquid supplying means to said header means, for starting the movement of said header means.

2. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside said gas stream and to one side of said electrodes, header means for washing said electrodes, said header means being normally positioned in said

space, liquid supply means for said header means, means for moving said header means from said space towards said electrodes, and means including thermostatic means responsive to the temperature of the liquid in said liquid supply means, and including means actuated by said header means when it moves to a position alongside said electrodes, for actuating said liquid supply means to supply liquid to said header means for spraying upon said electrodes.

3. An electrostatic precipitator as claimed in claim 2 in which the thermostatic means acts to stop the header moving means and the liquid supply means when the temperature of the liquid from the liquid supply means is below a predetermined minimum.

4. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside said gas stream and to one side of said electrodes, header means normally positioned in said space, means for moving said header means from said space alongside said electrodes, liquid supply means for said header means, damper means for preventing the flow of gas through said inlet and outlet, means for closing said damper means, means including means actuated by the closing of said damper means and including thermostatic means responsive to the temperature of the liquid from said liquid supply means for starting said header moving means, and means including means actuated by said header means when it moves to a position alongside said electrodes for actuating said liquid supply means to supply liquid to said header means for spraying upon said electrodes.

5. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside said gas stream and to one side of said electrodes, header means normally positioned in said space, means for moving said header means from said space alongside said electrodes, liquid supply means for said header means, damper means for preventing the flow of gas through said inlet and outlet, means for closing said damper means, an electric power supply connected to said electrodes, means including means actuated by the closing of said damper means for disconnecting said electrodes from said power supply and including thermostatic means responsive to the temperature of the liquid from said liquid supply means for starting said header moving means, and means including means actuated by said header means when it moves to a position alongside said electrodes for actuating said liquid supply means to supply liquid to said header means for spraying upon said electrodes.

6. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside said gas stream and to one side of the electrodes, header means for washing said electrodes, electrically operated valve means for supplying liquid

to said header means, said header means being normally positioned in said space, means for moving said header means from said space towards said electrodes, and means including an electric switch actuated automatically by said header means when it moves to a position alongside said electrodes, for energizing said valve means for supplying liquid to said header means for spraying upon said electrodes.

7. An electrostatic precipitator comprising a casing having a gas inlet and a gas outlet, damper means for preventing the flow of gas through said inlet and outlet, means for closing said damper means, electrodes in said casing between said inlet and outlet and in the path of the gas stream passing therethrough, said casing having an open space therein, offset with respect to said inlet and outlet and said electrodes, so as to be outside the gas stream and to one side of the electrodes, header means for washing said electrodes, electrically operated valve means for supplying liquid to said header means, said header means being normally positioned in said space, an electric motor for moving said header means, means including an electric switch actuated by the closing of said damper means for energizing said motor for moving said header means towards said electrodes, and means including an electric switch actuated automatically by said header means when it moves to a position in alignment with said electrodes, for energizing said valve means for supplying liquid to said header means.

8. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes so as to be outside the gas stream and to one side of said electrodes, header means normally positioned in said space, means including an electric motor for moving said header means from said space alongside said electrodes, liquid supply means including an electrically operated valve means for said header means, damper means for preventing the flow of gas through said inlet and outlet, means for closing said damper means, means including an electric switch actuated by the closing of said damper means for energizing said motor for starting said header moving means, and means including an electric switch actuated by said header means when it moves to a position alongside said electrodes for energizing said valve means to supply liquid to said header means for spraying upon said electrodes.

9. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside said gas stream and to one side of said electrodes, header means normally positioned in said space, means including an electric motor for moving said header means from said space alongside said electrodes, liquid supply means including an electrically operated valve for said header means, damper means for preventing the flow of gas through said inlet and outlet, means for closing said damper means, an electric power supply connected to said electrodes, means including an electric switch actuated by the closing of said

damper means for disconnecting said electrodes from said power supply and for starting said motor, and means including an electric switch actuated by said header means when it moves to a position alongside said electrodes for energizing said valve means to supply liquid to said header means for spraying upon said electrodes.

10. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside the gas stream and to one side of the electrodes, header means for washing said electrodes, said header means being normally positioned in said space, means including an electric motor for moving said header means from said space alongside said electrodes towards the other side thereof, means including an electric switch automatically operated by said header means when it reaches the other side of said electrodes for reversing said motor, and means including an electric switch automatically operated by said header means when it returns to said space for stopping said motor.

11. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes so as to be outside the gas stream and to one side of the electrodes, header means for washing said electrodes, said header means being normally positioned in said space, means including an electric motor for moving said header means from said space alongside said electrodes towards the other side thereof, liquid supply means including electrically operated valve means for said header means, means automatically operated by said header means when it reaches said one side of said electrodes for energizing said valve means for supplying liquid to said header means, means including an electric switch automatically operated by said header means when it reaches said other side of said electrodes for reversing said motor, means including an electric switch automatically operated by said header means when it passes said one side of said electrodes for deenergizing said valve means for stopping the supply of liquid by said liquid supply means to said header means, and means including an electric switch automatically operated by said header means when it returns to said space, for stopping said motor.

12. An electrostatic precipitator comprising a casing having a gas inlet and a gas outlet, electrodes in said casing between said inlet and outlet and in the path of the gas stream passing therethrough, said casing having an open space therein, offset with respect to said inlet and outlet and said electrodes, so as to be outside the gas stream and to one side of the electrodes, header means for washing the electrodes, said header means being normally positioned in said space, means including an electric motor for moving said header means from said space alongside said electrodes towards the other side thereof, means including an electric switch automatically operated by said header means when it reaches said other side of said electrodes, for reversing said motor, means including an electric switch automatically operated by said header means when it

returns to said space, for stopping said motor, and timing means energized by said header means when it returns to said space for deenergizing said motor for a predetermined period of time for preventing said header means from again being moved from said space for said predetermined period of time.
